UNITED STATES PATENT OFFICE.

HENRY J. BEHRENS, OF NEW YORK, N. Y.

IMPROVED MARINE GOVERNOR.

Specification forming part of Letters Patent No. 37,944, dated March 24, 1863.

To all whom it may concern:

Be it known that I, HENRY J. BEHRENS, of the city, county, and State of New York, have invented a new and Improved Marine Governor; and I do hereby declare that the following is a full, clear, and exact description of the same, reference being had to the accompanying drawings, forming a part of this specification, in which—

Figure 1 represents a longitudinal vertical central section of my invention, the line $x\ x$, Fig. 2, indicating the plane of section. Fig. 2 is a transverse vertical central section of the same, the plane of section being indicated by the line $y\ y$, Fig. 1.

Similar letters of both views denote like parts.

The object of this invention is to make an ordinary pendulum or ball governor available for marine engines, and to arrange the same so that the rolling and pitching of the vessel has no disturbing influence on the action of said governor.

The invention consists in combining with an ordinary pendulum or ball governor a universal joint or gimbal in such a manner that said governor will place itself always in a vertical position independent of the rolling or pitching motions of the ship, and that in consequence of this arrangement the action of the governor will be equally sure and correct in a rough and in a smooth sea.

The invention consists also in the arrangement of three bevel-wheels—one in the driving-shaft, one on one of the fulcrum-pins of the gimbal, and one on the top of the spindle of the governor—in such relation to each other and to the gimbal from which the governor is suspended that the correct position of said wheels in relation to each other is not disturbed by the motions of the vessel and consequent oscillating motions of the governor and frames to which the wheels are attached.

The invention consists, further, in arranging the rising-and-falling rod within the spindle of the governor in such relation to the gimbal that when the balls assume their mean position corresponding to the mean speed of the engine the top of said rod coincides with the common center of the gimbal, and, consequently, the motions of the vessel and consequent oscillating motions of the governor have

no influence on the position of the throttle-valve.

The invention consists, finally, in placing the rod which transmits the motion of the balls to the valve loosely on the top of the rising-and-falling rod, leaving the latter perfectly free to accommodate itself to the varying position of the vessel without disturbing its connection with said rod.

My invention will be perfectly understood by referring to the following description and accompanying drawings.

A represents an ordinary pendulum-governor, the balls B' of which are suspended from arms a , and these arms connect by links b with a sleeve, e , which is placed loosely on the hollow spindle d . A pin, e , connects this sleeve to the rod f , which rises and falls in the hollow spindle d as the balls fly out or sink down, according to the quicker or slower motion of the engine. The spindle d of the governor is suspended in a frame, B , which is provided with two projecting arms, g , that hang on pivots $h\ h'$. These pivots are firmly inserted into a frame, C , one opposite the other, and said frame is suspended at points opposite to each other and exactly between the pivots $h\ h'$ from a pivot, i , and from the driving-shaft j , the pivot i being inserted into one end of a frame, D , and the shaft j having its bearing in the other end of said frame. This frame is firmly bolted to some part of the engine or vessel and it supports the governor. The driving shaft j carries the bevel-wheel E , which gears into another bevel-wheel F , secured to the pivot h , from which the frame B is suspended, and through this bevel-wheel motion is imparted to a third bevel-wheel, G , secured to the top of the spindle d . It will be noticed that when the frame D oscillates its center of oscillation coincides with the center of the bevel-wheel E , and consequently the wheel F will always remain in gear with said wheel independent of the position of the frame D , and in the same manner the frame B oscillates on a center which coincides with the center of the wheel F , and the oscillations of said wheel, therefore, will not be able to disturb the correct position of the two wheels F and G in relation to each other; and the governor being suspended from the frames B C D , arranged like a gimbal, is at liberty to

place itself always in a vertical position, and it will, therefore, by its inherent gravity, maintain its vertical position independent of the rolling and pitching of the vessel. It will act with equal correctness in a smooth and in a rough sea. The rod *f*, which works within the hollow spindle *d*, is made of such a length that its top coincides with the universal center of the gimbal when the balls have assumed their normal position, and by these means the oscillations of the governor, caused by the rolling and pitching of the ship, have no disturbing effect on the position of the throttle-valve. The motions of the rising-and-falling rod *f* are transmitted to the throttle-valve by means of a rod, *l*, which rests loosely on the top of the rod *f*, being depressed by means of a weight or spring. Its lower end is flattened out so that it offers a broad bearing for the top end of the rod *f*, and that it is not liable of being thrown off of said rod by the motions of the ship and consequent swinging or oscillating motions of the governor. The rods *f* and *l* might, however, be connected to each other by a ball-and-socket joint, or in any other permanent manner; but it is obvious that by placing the rod *l* loosely on the top of the rod *f* all the labor which would otherwise be required for the purpose of effecting the connection is saved.

This governor is very simple in its construction, it can be put up in any convenient place in the engine-room, and its effect on the throt-

tle-valve will be just as sure in the roughest sea as on shore or on board a ship in the calmest weather or inside a harbor.

What I claim as new, and desire to secure by Letters Patent, is—

1. The combination, with an ordinary pendulum or ball governor, *A*, of a universal joint or gimbal, *B C D*, constructed substantially as herein described, for the purpose set forth.

2. The arrangement of the three bevel-wheels *E F G* with the driving-shaft *j*, pivot *h*, and spindle *d*, of the governor *A*, when the latter is suspended from a universal joint or gimbal, *B C D*, substantially as and for the purpose herein shown and described.

3. So arranging the rising-and-falling rod *f* with the governor *A* and universal joint or gimbal *B C D* that the top of said rod coincides with the universal center of the gimbal when the balls of the governor assume their mean position, substantially as and for the purpose specified.

4. Placing the rod *l*, which transmits the motions of the balls to the throttle-valve, loosely on the top of the rising-and-falling rod *f*, substantially as and for the purpose specified.

HENRY J. BEHRENS.
